Inventor:
William P. Couper

UNITED STATES PATENT OFFICE.

WILLIAM P. COUPER, OF WASHINGTON, DISTRICT OF COLUMBIA.

FOUNTAIN-PEN.

SPECIFICATION forming part of Letters Patent No. 602,829, dated April 26, 1898.

Application filed October 29, 1897. Serial No. 656,805. (No model.)

To all whom it may concern:

Be it known that I, WILLIAM P. COUPER, a citizen of the United States, residing at Washington, in the District of Columbia, have invented certain new and useful Improvements in Fountain-Pen Filling Attachments; and I do hereby declare the following to be a full, clear, and exact description of the invention, such as will enable others skilled in the art to which it appertains to make and use the same, reference being had to the accompanying drawings.

The object of my invention is to provide a fountain-pen with attachments for filling the pen, which attachments form a permanent part of the pen; and I have sought to reduce such a construction to the utmost simplicity compatible with convenient and efficient operation.

To this end my invention consists in the construction and combinations set out in the claims.

In the drawings, Figure 1 is a longitudinal sectional view of a fountain-pen containing my attachments. Fig. 2 is a side elevation of the feeder with the stem and piston formed thereon. Fig. 3 is a view of the cap or cover. Fig. 4 is a perspective view of the piston-cover and valve-seat; and Fig. 5 is a perspective view of the piston, the stem being broken near the piston.

The casing *a* has a cylindrical bore, and its exterior tapers toward the ends like a cigar. At the lower end the usual feeder-carrying sleeve *b* is screwed into the case *a*, and its exterior surface conforms to that of the case *a*. The pen *c* and feeder *d* are held in the sleeve in the usual manner, and the feeder has a capillary channel *e* for the ink. The upper end of the casing *a* is reduced and screw-threaded for a short distance at *f*, and beyond this reduced portion the casing is formed into a short nozzle *g*. A nozzle-cap *h* is threaded to screw on the upper end of the casing until it rests against and closes the mouth of the nozzle. If desired, a piece of rubber or cork may be placed in the nozzle-cap to more securely close the nozzle.

A stem *i* is formed on or attached to the feeder *d* and extends to a point near the upper end of the bore, where a piston *j* is formed on the stem. A piston-cap *k* is screwed on

the piston *j*, and this cap completely fills the bore.

A pocket *l l'* is formed partly in the piston-cap and partly in the piston, and a metal or rubber ball *o* of less diameter than the pocket occupies the pocket and seats itself in the part of the pocket *l* contained in the piston-cap, so that it closes an opening *m* in the cap, thus forming a valve. Passages *n* and *n* in the piston allow the ink to flow from the pocket *l l'* to the bore of the casing.

A screw *p* may be used to prevent the piston from leaving the casing, but it could be dispensed with, if desired.

The usual cap *q* is used to cover the pen-point when not in use, and it may be slipped over the upper end of the casing for safe keeping when writing is being done.

The operation of my attachment is as follows: When it is desired to fill the reservoir with ink, the nozzle-cap *h* is unscrewed and the feeder-sleeve *b* is removed. The nozzle *g* is then immersed in the ink, and the feeder is drawn up out of the casing, carrying with it the piston, the ink following the piston under atmospheric pressure. This motion is continued until the piston comes in contact with the screw *p*. The nozzle is now withdrawn from the ink, still keeping the casing vertical, but the ink will not flow out of the nozzle, because the piston and valve keep the casing air-tight. The nozzle-cap is now screwed to place, the casing still remaining vertical. The nozzle being closed, the piston is slowly forced back to its original position, the valve rising and allowing the ink to pass the piston through the passages in the piston. The feeder-sleeve is now screwed to place and the pen is ready for use.

It will be seen that with very little complication I have provided for filling the pen without the use of any parts other than those contained in the fountain-pen.

What I claim as my invention, and desire to secure by Letters Patent, is—

1. A fountain-pen having the usual writing appliances at one end of the casing and having a filling-nozzle at the other end, and means for filling the reservoir through the nozzle, substantially, as described.

2. A fountain-pen having a pen-point and feeder at one end and having a nozzle at the

opposite end, and having a piston within the casing for drawing the ink through the filling-nozzle and into the casing and a valve in the piston for permitting the ink to pass the piston, substantially, as described.

3. In a fountain-pen, the combination of a casing having a pen-point and feeder at one end, of a filling-nozzle at the opposite end of the casing, a stem secured to the feeder and extending substantially the length of the casing, a piston carried by the stem, and a valve in the piston and opening toward the stem, substantially, as described.

4. In a fountain-pen, the combination of a casing having a pen-point and feeder at one end, of a filling-nozzle at the opposite end of the casing, a stem secured to the feeder and extending substantially the length of the cas-

ing, a piston carried by the stem, a valve in the piston that opens toward the stem, a screw in the casing to limit the outward movement of the piston, substantially, as described.

5. In a fountain-pen, the combination of a casing having a pen-point and feeder at one end, and having a filling-nozzle at the opposite end, of a stem formed on the feeder, a piston on the stem, a valve in the piston that opens toward the stem, and a screw in the casing to limit the outward movement of the piston, substantially, as described.

In testimony whereof I affix my signature in presence of two witnesses.

WILLIAM P. COUPER.
